UNITED STATES PATENT OFFICE

GERARD B. LAMBERT, OF PRINCETON, NEW JERSEY, ASSIGNOR TO GILLETTE SAFETY RAZOR COMPANY, OF BOSTON, MASSACHUSETTS, A CORPORATION OF DELAWARE.

SAFETY RAZOR

Application filed May 27, 1932. Serial No. 613,903.

This invention relates to safety razors of the type in which a thin, flexible blade is clamped for shaving in operative position between cap and guard members. The convenience of users of such razors requires that the blade-positioning and clamping operations should be such that they may be quickly and conveniently carried out and also that the cap and guard may be easily separated to permit the removal and replacement of blades without obstruction.

In one aspect my invention consists in cap and guard members so constructed and arranged that these operations may be effected with an unusual degree of convenience and without entirely disconnecting the razor parts, thus avoiding the annoyance of loose parts which may become misplaced or lost. With this end in view, an important feature of my invention consists in cap and guard members which are inter-connected for relative longitudinal movement to cover or expose the blade, or the blade-supporting face of the razor, and also for relative movement toward and from each other to clamp or release the blade. A striking advantage of this novel construction is that a razor so constructed may be adapted to open itself automatically when the operator releases the clamping pressure upon the blade. For example, the cap may be unlocked and freed of frictional contact with the blade by merely turning a releasing screw, and thereupon, if the razor is held in an inclined position, the cap is free to slide endwise and expose the blade-supporting face of the razor or the used blade, as the case may be.

There are various ways in which the blade-clamping members of a safety razor may be connected to achieve the desired results, but as herein shown, one is provided with a longitudinally-extending guide and the other with a slide fitting therein whereby the blade may be exposed by a guided endwise movement of one member with reference to the other. A desirable result of this construction is that the movement of the cap to and from superposed position above the blade may be effected while the blade occupies a substantially flat position and may be so

controlled as to obviate danger of displacing the blade or impairing the sharpness of its shaving edge.

Another novel feature of my invention consists in cap and guard members having a sliding connection limiting them to endwise movement under certain conditions, and including also a hinge which becomes effective only after the blade or the blade-supporting face of the guard has been fully exposed, the hinge thereupon permitting the cap to swing to an inoperative position completely out of the user's way.

My invention also includes as a novel feature locking means for positively maintaining the cap and guard members in superposed or blade-registering position while they are being moved into blade-flexing or clamping position and while they maintain the blade in a condition of transverse curvature for shaving. As herein shown, the locking means is designed to permit the full range of relative clamping movement between the cap and guard members while maintaining them positively in superposed position and to release them for relative endwise movement only when they have been separated to an extent which substantially releases the blade from its curved condition and permits it to reassume its normal flat position. Such locking means contribute to the convenience of the user by preventing relative longitudinal movement of the cap and guard except under conditions when such movement may freely take place without frictional engagement with the interposed blade.

Other features of the invention relate particularly to the construction and interrelation of the cap and guard members. As herein shown, the handle is secured directly to the guard and the guard is designed to receive a guide or carrier member. The cap is provided with a slide arranged to run in the guide member and with a curved blade-shaping portion to which the slide is connected. Connection is established between the cap and guide member at both ends of the cap when the latter is moved into position in registration with the blade so that a balanced

blade-flexing pull may be transmitted to the cap in flexing or clamping the blade.

These and other features of the invention will be best understood and appreciated from the following description of a preferred embodiment thereof selected for purposes of illustration and shown in the accompanying drawings in which:—

Fig. 1 is a view of the head of the razor in end elevation and a portion of its handle;

Fig. 2 is a view of the razor in cross section;

Fig. 3 is a view in longitudinal section;

Fig. 4 is a view in cross section showing the cap in blade-releasing position;

Fig. 5 is a view in perspective showing the cap in a partially displaced position;

Fig. 6 is a view in side elevation showing the cap in position fully to expose the blade;

Fig. 7 is a view in longitudinal section with the parts in substantially the same position shown in Fig. 5, and

Fig. 8 is a plan view of the razor with portions broken away showing the cap in its fully displaced position but before it has been moved angularly.

The illustrated razor comprises a guard member 10 having a flat, blade-supporting surface bounded by spaced parallel shoulders 14 over which the blade is flexed by the cap. The longitudinal edges of the guard are provided with guard teeth 12 of usual construction. The blade-receiving face of the guard is provided with a pair of spaced blade-locating projections 16, herein shown as being diamond-shaped in outline. The guard 10 is rigidly secured to or made integral with a forked head 18 which, with the barrel 20 constitutes the handle of the razor.

An elongated guide member 22 is movably mounted in the space between the forks of the head 18 beneath the blade-engaging face of the guard 10. A guide track 24 is formed in the upper face of the guide member 22 and extends longitudinally from one end thereof to the other, and this track has undercut flanges extending along its opposite longitudinal edges for the reception of a slide which will be presently described. The guide member 22 is held against longitudinal movement and prevented from being displaced endwise in the forked head 18 by a spindle 30 which is housed within the barrel 20 of the handle and passes upwardly through a bore in the head 18. At its upper end, it is riveted into the bottom of the guide member 22. The spindle 30 is threaded at its lower end to receive a knurled nut 32 and this is retained in place by an annular flange upon the lower end of the barrel 20 which enters a circular groove in the body of the nut. It will be seen that by turning the nut 32 and moving the spindle 30 up or down, a corresponding movement is imparted to the guide member 22 between the forks of the head 18.

The guide member 22 is provided at its left-

hand end, as seen in Figs. 3 and 6, with an upstanding ear 26 which terminates in an overhanging lip 28. At its other end, it is provided with a pair of stop pins 25 which project into the guide track 24 at its right-hand end, as shown in Figs. 6 and 8. At the same end, the guide member 22 is provided with a square notch opening through the bottom face thereof.

The cap comprises an elongated member 34 having a concave blade-shaping face with parallel, longitudinal edges which co-operate with the shoulders 14 of the guard in maintaining the flexible blade in a position of pronounced transverse curvature when the parts are positioned in shaving relation. The blade-shaping member of the cap is connected through a neck 36 at its outer end with a slide member 38, having, at either edge, laterally-projecting flanges 39 which fit in the undercut ways of the track 24 of the guide member 22. The flanges 39 terminate somewhat short of the left-hand end of the slide 38 and a cross pin 37 is provided therein at its extreme end and this extends from wall to wall of the track 24 and limits the endwise blade-exposing movement of the cap by encountering the stop pins 25, as indicated in Fig. 8. It will be noted that the cap is guided in a rectilinear path so long as the flanges 39 of its slide are moving within the track 24, but when the cap member has been displaced endwise to the limit of its blade-exposing movement, the end of the slide 38 is positioned over the notch in the end of the guide member 22 so that the cap member is free to swing from the position shown in Fig. 8 to the inoperative position shown in Fig. 6. Since angular displacement of the cap is positively prevented until it has been moved to the limit of its blade-exposing movement, all possibility is avoided of the cap touching the blade and displacing it or dulling its shaving edge.

The cap member 34 is provided at its left-hand end, as shown in Figs. 3 and 7, with a recess forming a lip 40 which is arranged to interlock with the overhanging lip 28 of the guide member when the cap is moved fully into superposed position above the guard 10. The slide member 38 of the cap is provided with a vertical hole 42 and this is arranged to be brought into alignment with a stationary pin 44 set in the forked head 18 and projecting upwardly into the throat thereof. The pin 44 constitutes a locking device for positively holding the cap member against displacement when the latter has been moved into blade-engaging position and drawn down toward blade-flexing position. The upper end of the locking pin 44 clears the lower face of the slide 38 by a slight amount only so that, as soon as the head 32 is turned to lower the guide member 22, the pin 44 will immediately enter the hole 42.

and lock the cap and guard members positively in alignment, while, at the same time, permitting them to be moved relatively toward and from each other to flex the blade and to regulate the degree of flexing and consequently the amount of edge exposure of the blade with respect to the guard.

A blade 46 suitable for use with the razor above described is shown in Fig. 8. The blade 10 is of thin, flexible and resilient steel sharpened at its opposite edges for shaving and provided at each corner with a recess defining elongated, unsharpened portions at each end of the blade. The blade is also provided 15 with an elongated slot 28 containing spaced, diamond-shaped apertures designed to fit the blade-locating projections or studs 16 of the guard.

The manner of using the illustrated razor 20 will be clear from the foregoing description but may be summarized as follows:

Assuming that the cap occupies the position shown in Fig. 6, it will be apparent that the blade-receiving face of the guard 10 is 25 fully exposed and that the blade 46 may be conveniently positioned thereon by the user. Having positioned the blade, the cap member is swung upwardly about the axis of the cross-pin 37 to a position in alignment with 30 the guard, as shown in Fig. 8. The cap member is then pushed toward the left, the slide 38 entering the track of the guide member 22. In this movement, the blade-shaping member 34 of the cap is brought into superposed relation with the blade 46, the movement of the cap continuing until the lip 40 is brought beneath the overhanging lip 28 of the guide member 22. In this position, the hole 42 in the slide 38 registers with the 35 stationary pin 44 in the forked head 18 of the handle. In this position, the blade-shaping member 34 of the cap clears, or barely touches the unflexed blade 46 supported on the face of the guard 10. Having moved the 40 cap into its superposed position above the blade, the knurled nut 32 is turned to draw the spindle 30 downwardly, carrying with it the guide member 22 and the cap member of 45 which the slide 38 is now fully contained within the guide member. The nut 32 may be 50 turned to depress the cap 34 to the limit of its blade-flexing movement, this being the position in which the blade is directly engaged between the shoulders 14 of the guard 55 and the curved blade-shaping face of the cap. This corresponds to the position of maximum 55 transverse curvature in the blade and minimum edge exposure. The user is, however, free to increase the amount of edge exposure 60 by releasing the spindle and cap slightly by turning the knurled nut 32 reversely, whereupon, the blade 46 is permitted slightly to straighten or flatten out, thereby increasing 65 its effective width and edge exposure. During 70 this adjusting movement, the locking pin 44 moves in the hole 42 of the slide 38 so that the cap and guard are continuously maintained against possibility of endwise relative displacement.

It will be noted that, when the cap is moved 70 toward the left in the razor, the overhanging lip 28 of the longitudinally stationary guide member 22 interlocks with the lip 40 of the slide 38, thus serving as a stop to determine the operative or blade-registering position of 75 the cap member 34. The connection thus established at the left-hand end of the cap member and the permanent connection afforded by the neck 36 at its right-hand end 80 serve to transmit a balanced straight-line pull 85 to the cap member 34 in flexing and clamping the blade.

When the user is ready to expose the blade 90 for purposes of cleaning or replacement, the knurled nut 32 is turned reversely, elevating the spindle 30, the guide member 22 and the cap member 34 with reference to the stationary guard 10. The pin 44 maintains its locking engagement with the hole 42 of the slide until the cap member 34 has been raised 95 sufficiently substantially to disengage the blade 46 after the latter has been permitted to reassume its normal flat condition upon the blade-supporting face of the guard. Thereupon, the cap member becomes unlocked 100 and is free to slide endwise to the position shown in Fig. 8 for fully exposing the blade and thereafter to be tilted into the angular position shown in Fig. 6.

If the razor is held in a position inclined 105 downwardly toward its right-hand end, or away from the ear 26, when the locking pin 44 is disengaged from the slide 38 and the flexing pressure of the cap member 34 relieved, then the whole cap immediately slides 110 outwardly to the limit of its endwise guided movement and rocks downwardly into its inoperative position, as shown in Fig. 6. All this takes place automatically or under the influence of gravity without any further manipulation or attention on the part of the user.

Having thus described my invention, what I claim as new and desire to secure by Letters 115 Patent of the United States is:—

1. A safety razor having cap and guard members provided respectively with concave and convex co-operating blade-shaping faces adapted to flex and clamp a flexible blade therebetween, said members being interconnected by longitudinal guiding means whereby said members are guided for relative rectilinear movement to cover or uncover the blade and for relative movement toward and from each other to clamp or release the blade.

2. A safety razor having cap and guard members provided respectively with concave and convex co-operating blade-shaping faces adapted to flex and clamp a flexible blade therebetween, said members having inter-

- connected longitudinal guides and one member being guided on the other for rectilinear movement into and out of superposed relation, and means for moving said members 5 toward and from each other to clamp or release an interposed blade.
3. A safety razor comprising cap and guard members having respectively concave and convex faces co-operating to flex and 10 position a flexible blade therebetween, one member including a longitudinally-extending guide and the other a slide fitting therein, whereby the blade may be uncovered by guided endwise bodily movement of one 15 member with reference to the other.
4. A safety razor comprising a flexible blade, and co-operating blade-clamping devices having co-operating blade shaping faces engaging the blade to position and flex 20 the blade between them, one of said devices having a longitudinal slide portion disposed parallel to and spaced from its blade-engaging face, and the other device having a co-operating guideway spaced from its blade-engaging face.
5. A safety razor comprising co-operating blade-clamping devices shaped to flex between them a resilient blade, one of said devices including an elongated longitudinal 30 slide spaced from its blade-engaging face, and the other having a guide member for receiving said slide and being mounted for bodily rectilinear movement toward and from the blade-engaging face of said device.
- 35 6. A safety razor comprising co-operating cap and guard members having opposed curved faces shaped to flex between them a resilient blade, said members being connected for relative lengthwise sliding from a superposed relation with the blade between them to an end-to-end position in which the blade is fully exposed, and means for drawing the cap and guard together when in superposed relation.
- 40 7. A safety razor comprising co-operating cap and guard members having opposed concave and convex faces respectively shaped to flex between them a resilient razor blade, a slide connecting said members whereby one 45 may be displaced endwise with respect to the other to expose the blade-supporting face of one member, and a hinge connection whereby the cap may be swung into inoperative position after such endwise displacement.
- 50 8. A safety razor comprising a guard member, a cap having a sliding connection therewith whereby the cap may be displaced endwise from a superposed position above the blade to a position in which the blade is exposed, said connection being arranged to maintain the cap and guard in parallel relation until the blade is fully exposed and including a hinge whereby the cap may be 55 swung below the guard thereafter.
9. A safety razor comprising co-operating cap and guard members shaped to flex between them a resilient blade and being connected for relative endwise movement, and means intermediate the ends of the members 70 for locking said members against endwise movement when in superposed relation with a blade flexed between them, the locking means being arranged to leave said members free for blade-flexing movement toward and from each other.
10. A safety razor comprising blade-clamping members shaped to flex between them a resilient blade and being connected for relative endwise movement, means for 75 positioning said members in superposed relation with a blade between them, means for relatively moving said members toward each other to flex the blade, and locking means rendered operative by such relative movement of said members.
11. A safety razor comprising blade-clamping members shaped to flex between them a resilient blade and being connected for relative endwise movement, means for 80 relatively moving said members toward each other while in contact with the blade, and means for positively locking said members in registration with each other while being so moved, said second named means being 85 arranged to release the blade-clamping members when they have been separated from blade-flexing position.
12. A safety razor comprising blade-shaping members connected for endwise rectilinear movement to and from superposed position with a flat blade between them, means for moving said members toward each other to flex the blade, and means for positively locking said members against endwise movement when the blade is flexed by them.
13. A safety razor comprising blade-shaping members connected for endwise movement to and from superposed position upon opposite sides of a flat interposed blade, 90 means for maintaining said members in shaving relation with the blade clamped in a position of pronounced transverse curvature, and locking means for said members arranged to release them for their endwise movement only when the blade is released sufficiently to 95 reassume a substantially flat condition.
14. A safety razor comprising a stationary guard, a cap connected thereto for endwise sliding movement to and from superposed position, means for spacing the cap from the guard so that a flat flexible blade may be interposed, means for drawing the cap toward the guard to flex the blade thereon, and a locking pin arranged to enter a part of the cap when it is moved into blade-flexing position.
15. A safety razor comprising a guard having a blade-shaping face, a guide member movable toward and from said face of the 100

guard, a slide longitudinally movable in the guide member, and a blade-shaping cap member connected to the slide.

16. A safety razor comprising a guard having blade-flexing shoulders in one face thereof, a guide member mounted for movement toward and from the other face of the guard, and a U-shaped cap member having a slide portion movable in the guide member and an overhanging portion with a concave blade-flexing face arranged to be positioned opposite to said shoulders.

17. A safety razor comprising a guard having a blade-supporting face, a guide member mounted beneath the guard and having a stop at one end projecting above the face of the guard, a cap member having one part sliding in the guide member beneath the guard and a blade-flexing part movable above the face of the guard and limited in its travel by said stop.

18. A safety razor comprising a guard having a blade-supporting face, a cap having a slide portion mounted for endwise movement below the face of the guard and an overhanging blade-flexing portion, the cap being movable endwise to embrace the guard between said portions thereof, and means for moving the overhanging portion of the cap to flex the blade.

19. A safety razor comprising blade-flexing members arranged to engage between them a resilient blade, said members having coacting longitudinal guides one of said members being movable and guided endwise by said guides with respect to the other to uncover completely an interposed blade, and means for establishing a clamping connection at both ends of one of said members for moving it toward or from the other.

20. A safety razor comprising a guard having a blade-supporting face, a cap having a co-operating blade-flexing face and being connected to the guard for guided endwise movement and also swinging movement with respect thereto, means for locking said cap and guard in superposed position operating to release the cap whereby it may first slide and then swing by gravity fully to expose the blade-supporting face of the guard.

GERARD B. LAMBERT.
